ICE CUBE TRAY

Logan L. Mallard, Norfolk, Va., assignor of one-half to H. Clay Hofheimer II, Norfolk, Va.

Application April 27, 1938, Serial No. 204,646

6 Claims. (Cl. 62—108.5)

1

This invention relates to ice cube trays for refrigerators.

As is well known, mechanical refrigerators are furnished with two or more ice cube trays receivable in the refrigerating units to provide ice cubes for various uses. These ice cube trays usually are formed entirely of metal or of rubber and while the latter are advantageous in that they permit the ready removal of the cubes from the tray, they are disadvantageous in that they require a substantially greater time for the freezing of the cubes. While the conventional all-metal tray is advantageous in that it permits faster freezing due to the more rapid rate of heat transfer, it is disadvantageous for the reason that much of the effective cold is lost by the necessity for running water over the bottom of the tray, or immersing the tray in water, in order that the cubes may be released.

An important object of the present invention is to provide a novel metal ice cube tray which is operative to permit the quick releasing of the cubes from the tray.

A further object is to provide a novel single operating handle and mechanical connections operated thereby for simultaneously releasing all of the cubes from the tray and the grid structure arranged therein.

A further object is to provide a novel grid structure and operating means therefor whereby the grid structure is readily movable relative to the tray to release the ice cubes from the latter and wherein the elements of the grid structure are movable away from each other to facilitate the release of the ice cubes from the grid structure.

A further object is to provide a device of this character having positive means for separating or ejecting the ice cubes from the grid structure after separating the cubes from the tray.

A further object is to provide a novel cam and lever mechanism for an ice cube tray which has a single operating handle initially movable with substantially great leverage to initially break the ice cubes loose from the tray, and subsequently movable with a lesser leverage to separate the ice cubes from the grid structure.

A further object is to provide a novel structure of the character referred to wherein the operation of the single lever breaks the ice cubes loose from the tray and subsequently from the grid structure to loosely deposit all of the cubes in the tray to be subsequently individually handled as desired.

Other objects and advantages of the invention

will become apparent during the course of the following description.

In the drawing I have shown two embodiments of the invention. In this showing—

Figure 1 is a perspective view showing all of the parts in normal position,

Figure 2 is a central vertical longitudinal sectional view showing the parts in cube releasing position, parts being shown in elevation,

Figure 3 is a similar view showing the initial operation of the parts, a portion being broken away,

Figure 4 is a transverse vertical sectional view substantially on line 4—4 of Figure 1,

Figure 5 is a detail perspective view of a pair of the cube ejecting elements, and,

Figure 6 is a detail perspective view of a modified form of cube ejecting device and its associated transverse grid element.

Referring to the drawing, the numeral 10 designates an individual ice cube tray having a bottom 11, end walls 12 and side walls 13, the end and side walls preferably diverging upwardly, as shown. The ice tray forms no part of the present invention per se and may be of any desired form:

A grid structure is arranged within the tray and comprises a plurality of individually integral transverse members 14 and a plurality of separate aligned longitudinal members 15. Each of the transverse members 14 is provided with an opening 16 at a point spaced from the upper edge of the member and centrally of the width of the tray, for a purpose to be described. The transverse members 14, when in the normal position shown in Figure 3, preferably slightly diverge toward the bottom of the tray.

Each adjacent pair of longitudinal grid members 15 is provided with a combined connecting and ejecting unit 17, and each of these units comprises a pair of identical plates 18 adapted to lie against opposite faces of the associated longitudinal members 15. Each plate 18 is provided with a head end 19, the upper edge of which is normally flush with the upper edge of the associated member 15. One end of the head 19 of each of the plates 18 is approximately squared off as at 20 to provide an edge lying against or in close proximity to the adjacent face of the associated grid member 14. The opposite end of each head 19 is provided with a sloping edge 21 for a purpose to be described.

Each plate 18 is provided with a reduced end 22 and the reduced ends of each pair of plates 18 extend through one of the openings 16, as

shown in Figure 3. The ends 22 of each pair of plates are riveted or similarly secured as at 23 against opposite faces of one of the members 15. The head ends of each pair of plates 18 are pivotally connected by a pin 24 to the adjacent grid member 15, the heads of the pins 24 preferably being countersunk and flush with the outer faces of the plates 18. Above the projecting end 22 of each pair of plates 18 is a filler plate 25 extending from the upper edge of the associated end 22 to the top of the associated member 15 and having its upper edge flush with the latter. The ends of the extensions 22 and the corresponding ends of the filler plates 25 are sloped as at 26 to form a continuous edge lying against the edge 21 of the next adjacent plate 18. The filler plates 25 are employed to prevent ice from forming above the extensions 22 and thus rendering it difficult to remove the ice cubes, as will become apparent.

Each of the grid members 15 adjacent the ends of the tray is provided with an upwardly extending portion 27 and bell crank levers 28 and 29 are pivotally connected to the respective projections 27 as at 30. Each bell crank lever is formed of a pair of plates arranged on opposite sides of the projections 27 as shown in Figure 1 for the purpose of providing additional strength and properly distributing the forces involved in the operation of the device, but each pair of plates may be considered, in effect, to be a single bell crank lever. The levers 28 and 29 are respectively provided with oppositely extending arms 31 normally everhanging the upper edges of the ends of the tray as shown in Figure 1.

The other arm 32 of each bell crank lever normally projects downwardly for connection with operating means to be described. The opposite plates of each bell crank lever have the depending arms thereof connected by a pin 33 operating in a slot 34 in the respective projection 27. These pins have pivotal connection with the arms of yokes 35 carried by the remote ends of respectively front and end lengths 36 and 37. The inner end of the link 37 is pivotally connected as at 38 to a pair of spaced side plates 39, the adjacent end of the link 37 lying between these plates as shown in Figure 1.

The inner end of the link 36 also lies between the plates 39 and is provided with a pin 40 extending through slots 41 formed in the plates 39. An operating lever 42, preferably of elongated U-shaped has the sides thereof normally lying parallel and in close proximity to the edges of the link 37, and the lever 42 is pivotally connected near its operating end on the pin 38. A pair of spaced operating links 43 are pivotally connected at their ends respectively to the pin 40 and to pins 44 connected to the respective ends of the arms of the lever 42. The distance between the pins 38 and 44 is preferably substantially shorter than the distance between the pin 38 and the pin 40, when the latter is at the inner end of the slots 41, for a purpose to be described.

A slightly modified form of the invention is shown in Figure 6 of the drawings, such form permitting the plates 18 and the filler plates 25 to be made integral. In the form of the invention previously described, the openings 16 are stamped through the solid sheets forming the plates 14. In the form shown in Figure 6 the transverse grid plates 14 are provided with similar openings 45, but the upper edge of the plate 14 is cut from the top of the plate 14 to the opening 45 as at 46. The plate is also cut parallel

4 to its upper edge as at 45' to form a lip 46' for a purpose to be described.

The connecting and ice ejecting means in Figure 6 comprises a pair of side plates 47, each of which is slotted in its upper edge as at 48 to receive the portion of the corresponding plate 14 which projects inwardly toward the cut 46. When so formed, each plate 47 corresponds in shape to one of the plates 18 and its associated filler plate 25. Opposite ends of the plates 47 are sloped as at 49 and 50, each slope 50 being normally arranged in contact with the slope 49 of the next adjacent plate 47.

The operation of the form of the device shown in Figures 1 to 5 inclusive is as follows:

The tray is filled with water to the proper level, slightly below the upper edge of the tray, and the tray is placed in the refrigerator with all of the parts in the position shown in Figure 1. After 20 the water has frozen into the pieces defined by the pockets in the tray between the grid elements and it is desired to release the cubes, the tray is removed from the refrigerator and preferably placed on a suitable supporting surface. 25 The free end of the operating lever 42 is then lifted and since the pivots 38 and 44 are relatively close together while these pivots and the pivot 40 are arranged in a common plane, it will be apparent that initial movement of the free end 30 of the lever 42 provides very great leverage exerting an inward pull on the links 36 and 37. This initial leverage permits the turning of the bell crank levers 28 and 29 without the exercise of substantial force on the lever 42.

35 It will be apparent that the bell crank lever 28 turns in a counter-clockwise direction while the bell crank lever 29 turns in a clockwise direction, and accordingly the outstanding arms 31 of the bell crank levers exert a great downward force on the upper edges of the ends of the tray. The accompanying upward reaction transmitted to the projection 27 causes the ends of the grid structure to move upwardly, thus breaking the ice cubes at the end of the tray away from the 45 bottom of the tray.

It will be apparent that the continued turning movement of the lever 42 from its initial position increases the angular relation between the front end of the lever 44 and the link 43, thus progressively reducing the effective leverage. However, by the time this leverage is materially reduced all of the ice cubes will have been broken loose from the tray. After the pin 40 reaches the inner ends of the slots 41 the links 43 cease to 55 turn with respect to the lever 42 and the latter transmits direct motion to the plates 39 to move the pivot pin 38 toward the left and the pivot pin 40 toward the right. When the pin 40 reaches the inner ends of the slots 41, the bell crank lever pins 33 reach the inner ends of their slots 34 and accordingly the bell crank levers cease to turn about their pivots 30. Therefore it will be apparent that the turning movement of the lever 42 beyond the point at which the pin 40 60 initially engages the inner ends of the slots 41 transmits a direct pull to the upwardly projecting portions 27 of the end grid members 15. Such turning movement of the lever 42 therefore causes the adjacent grid sections to turn about their pivot pins 44, as shown in Figure 2, thus causing the portions of the grid members 14 below the pivots 24 to swing away from each other to tend to disconnect the ice cubes from the plates 14.

It will be apparent that the head ends 19 of the plates 18 extend a substantial distance be-

yond and below the respective pivot points 24. As shown in Figure 2, therefore, such portions of the plates 18 move downwardly with respect to the extended ends 22 of the next adjacent plate 18 and accordingly act as ejectors by positively breaking the ice cubes loose from the longitudinal grid members 15. This downward forcing of the ice cubes obviously will break them loose from any adhesion to any other parts of the device, such as the projections 22 of the filler plates 25. The head ends of the plates 18 at the left hand side of the apparatus as viewed in Figure 3 perform the same result with respect to the adjacent ice cubes. While no ejector element is employed in the right hand end of the tray, as viewed in Figure 3, the motion of the yoke 35, upon swinging movement of the bell crank lever 29 will accomplish the same result. Accordingly it will be apparent that all of the ice cubes, upon one complete swinging movement of the lever 42 to the position shown in Figure 2, will be completely disengaged from the tray and from the grid structure, thus depositing them loosely in the tray for individual use.

The form of the invention shown in Figure 6 does not affect the operation described but merely provides an alternative arrangement whereby the means connecting the adjacent plates 15 and acting as cube ejectors may be made in unitary plates instead of in separate plates 18 and 25. The projections 22 are formed on the plates 18 for insertion through the openings 16 whereupon the filler plates are riveted or otherwise secured to the grid members 15. In the form of the invention shown in Figure 6, the plates 41 may be inserted into the opening 45 of each plate 14 by turning aside the lip 46 whereupon such lip may be bent back in any suitable manner into the slots 48.

It will be noted that there is some slight play provided between the opposite surfaces of each plate 14 and the adjacent inner edges of the head 19 and filler plate 25 (or between the opposite edges of the notches 48 in Figure 6) and there is also some play provided between such portions of the plate 14 and the adjacent edges of the adjacent grid sections 15 to permit the latter, above the pivots 24, to swing toward each other to permit the parts to assume the position shown in Figure 2. Accordingly when such position of the device is reached, the plates 14 will approximately bisect the angles between the adjacent edges of the adjacent plates 15.

From the foregoing it will be apparent that the present device provides novel and highly effective means for quickly disconnecting all of the ice cubes from a freezing tray to permit them to be individually used or stored for future use. The cubes are loosely dropped into the tray by a single swinging movement of the lever 42 from the position shown in Figure 1 to the position shown in Figure 2, and an initial very great leverage is provided when it is most greatly needed, to break the ice cubes loose from the tray. The device has been found to be operative with so little force as to permit its use and operation by a fairly small child.

It is to be understood that the forms of the invention herewith shown and described are to be taken as preferred examples of the same and that various changes in the shape, size and arrangement of parts may be resorted to without departing from the spirit of the invention or the scope of the subjoined claims.

I claim:

1. An ice cube tray comprising a receptacle, a grid structure arranged in said receptacle and comprising a substantially vertical longitudinal separator formed of a plurality of sections pivotally connected for movement in the vertical plane of said separator, and a plurality of transverse sections connected for relative movement with respect to said longitudinal sections, a pair of normally aligned links, means connected to the remote ends of said links to transmit a downward force to the adjacent ends of the receptacle and thus generate an upward reaction tending to swing the remote longitudinal sections upwardly to pivot said longitudinal sections with respect to each other upon movement of the inner ends of said links toward each other, and means for effecting movement of the inner ends of said links toward each other.
2. An ice cube tray comprising a receptacle, a grid structure arranged in said receptacle and comprising a substantially vertical longitudinal separator formed of a plurality of sections pivotally connected for movement in the vertical plane of said separator, and a plurality of transverse sections connected for relative movement with respect to said longitudinal sections, a pair of normally aligned links, means connected to the remote ends of said links to transmit a downward force to the adjacent ends of the receptacle and thus generate an upward reaction tending to swing the remote longitudinal sections upwardly to pivot said longitudinal sections with respect to each other upon movement of the inner ends of said links toward each other, and lever means for effecting movement of the inner ends of said links toward each other and constructed and arranged to provide a relatively great initial leverage ratio followed by a relatively lower leverage ratio.
3. An ice cube tray comprising a receptacle, a grid structure arranged in said receptacle and comprising a substantially vertical longitudinal separator formed of a plurality of sections pivotally connected for movement in the vertical plane of said separator, and a plurality of transverse sections connected for relative movement with respect to said longitudinal sections, a pair of normally aligned links, means connected to the remote ends of said links to transmit a downward force to the adjacent ends of the receptacle and thus generate an upward reaction tending to swing the remote longitudinal sections upwardly to pivot said longitudinal sections with respect to each other upon movement of the inner ends of said links toward each other, a pair of connecting links, a pin pivotally connecting one end of each of said pair of links to the inner end of one of said first named links, the other ends of the links of said pair having slots therein, a pin extending through said slots and through the inner end of the other of said first named links, a handle lever normally substantially horizontally arranged and pivotally mounted adjacent one end on said first named pin, a pair of motion transmitting links each having one end connected to said second named pin, and pins connecting the other ends of said last named pair of links to said end of said lever, all of said pins lying substantially in a horizontal plane when said lever is in normal position.
4. An ice cube tray comprising a receptacle, a grid structure arranged in said receptacle and comprising a substantially vertical longitudinal

separator formed of a plurality of sections pivotally connected for movement in the vertical plane of said separator, and a plurality of transverse sections connected for relative movement with respect to said longitudinal sections, a pair of normally horizontal aligned links having their adjacent ends spaced from each other, a bell crank lever pivotally connected to each of the remote longitudinal sections and provided with an outstanding arm overhanging the upper edge of the adjacent end of said receptacle, each bell crank lever having a depending arm pivotally connected to the adjacent outer end of the adjacent link whereby movement of the inner ends of said links toward each other will swing the first named ends of said bell crank levers downwardly and transmit an upward reaction to the remote longitudinal sections to swing said longitudinal sections about their pivots, and lever means for effecting movement of the inner ends of said links toward each other.

5. An ice cube tray comprising a receptacle, a grid structure in said receptacle formed of separate aligned vertical longitudinal sections and a plurality of substantially vertical transverse sections, connecting means between adjacent longitudinal sections, each such means having a portion connected to one end of one longitudinal section and extending over and pivotally connected to the upper extremity of the adjacent end of the adjacent longitudinal section, each transverse section having an opening receiving the associated connecting means, and means for swinging said longitudinal sections upwardly about their pivots, the adjacent ends of said longitudinal sections being constructed and arranged to cause each transverse section to assume a position substantially bisecting the angle between the adjacent ends of the adjacent longitudinal sections upon swinging movement thereof to a predetermined extent, to separate the ice cubes from the grid structure and from said tray.

6. An ice cube tray comprising a receptacle, a grid structure in said receptacle formed of a

plurality of separate aligned vertically disposed longitudinal sections and a plurality of substantially vertically disposed transverse sections, connecting means between adjacent longitudinal sections, each such means having a portion connected to one end of one longitudinal section and extending over and pivotally connected to the adjacent end of the adjacent longitudinal section at the upper extremity thereof, each connecting means having a reduced portion and each transverse section having an opening receiving such reduced portion to loosely support said transverse section, and means for swinging said longitudinal sections upwardly about their pivots, the adjacent ends of said longitudinal sections being constructed and arranged to cause each transverse section to assume a position substantially bisecting the angle between the adjacent ends of the adjacent longitudinal sections upon swinging movement thereof to predetermined extent to separate the ice cubes from the grid structure and from said tray, each connecting means extending beyond its pivotal connection to form a portion relatively movable over the face of the associated longitudinal section to assist in separating ice cubes from the latter.
